W. W. Payne

Attorney

UNITED STATES PATENT OFFICE.

MICHAEL BOTTINO, OF AUBURN, NEW YORK.

COMMUTATOR.

Application filed December 29, 1920. Serial No. 433,938.

To all whom it may concern:

Be it known that I, MICHAEL BOTTINO, a citizen of the United States, residing at Auburn, in the county of Cayuga and State 5 of New York, have invented certain new and useful Improvements in Commutators, of which the following is a specification.

The present invention relates to commutators for internal combustion engines and 10 consists in the combinations and arrangements of elements hereinafter described, and particularly set forth in the accompanying claim.

The invention has for its purpose to provide 15 a structure of commutator adapted for effecting a spark in some one cylinder of the engine to the end of starting the engine without the necessity of cranking.

Another object of the invention is to provide 20 a commutator wherein the spark is prolonged, thereby insuring ignition and avoiding the formation of carbon in the cylinders.

It is further proposed to provide the commutator with a fixed or stationary part for 25 connecting with the wires leading to the coils, thereby leaving the adjustable portion unencumbered and thus avoiding the breaking of the wires which occurs after constant retarding and advancing of the spark 30 where the wires are attached to the movable commutator part.

The invention is disclosed by way of illustration in the accompanying drawings wherein:

Figure 1 is a sectional view taken through 35 a commutator constructed in accordance with my invention.

Figure 2, an elevation of the cap member showing the contact brushes.

Figure 3, an elevation of one side of the 40 ring portion as taken on the line 3-3 of Figure 1.

Figure 4, an edge view of the ring, and 45 Figure 5, a view similar to Figure 3 taken on the line 5-5 of Figure 1.

Referring to the construction in further detail and with like reference characters designating corresponding parts in the different views shown, 6 represents a cylindrical portion or ring having a band of insulating material 7 secured on its inner surface by the several screws 8, or otherwise; and segmental contacts 9 are embedded within the insulating band 7 as shown. The 55 segments of the contact 9 are each of ap-

proximately ninety degrees (90°), and are separated by the small insulated portions 10 for the purpose hereinafter described.

The portion 6 has one edge cut away as 60 at 11 to receive the complementary edge 12 of the cap 15, and a ring 14 of insulating material is secured within said cap by the several binding posts 13 as shown. Each binding post holds a spring contact member 16 in engagement with the inner flange portion 65 of each contact segment 9. There are, of course, as many binding posts as there are conductor segments 9. The four binding posts 13 cooperate with the wiring leading to the spark plugs in the well known manner, current being supplied to the contact roller 19 on the arm 18 of the shaft in the usual way.

It will be obvious, of course, that by making the necessary alterations, the device may 70 be employed on engines having any number of cylinders, the alterations merely residing in changing the number of contacts and binding posts, together with the parts co-operating therewith.

It will also be readily understood from the foregoing that to start an engine by means of this commutator, it will be necessary only to move the ring 6 by means of the adjusting member 20 until the segment 85 9 that controls the cylinder having gas under pressure, is reached by the contact roller 19, thereby completing the electric circuit and producing a spark to ignite the charge and start the engine to function.

The illustration shows a particular embodiment of the invention though it is understood, of course, that the invention may be carried out in other ways, and that therefore the present disclosure is to be considered in an illustrative sense only and not as a limiting one.

Having thus described my invention, what is claimed as new is:

A commutator comprising a stationary 100 member having an insulating ring with a plurality of radial openings therethrough spaced about the same, a binding post having an enlarged head located within each of said radial openings, a resilient contact finger secured beneath said enlarged head of each of said binding posts, said contact finger having a portion extending outwardly at an angle from the head of said binding post said outwardly extending portion 105 110

being bent inwardly to provide a rounded end, an oscillatory member supported in end to end relation to said stationary member, said oscillatory member having a ring of insulating material with a plurality of arcuate contact segments embedded in its surface, each of said contact segments having a radially extending flange in engagement with the rounded end of one of said resilient

contact fingers, and a rotating shaft having 10 a contact member thereon adapted to make electrical connections with said contact segments during the revolution of said shaft, substantially as set forth.

In testimony whereof I affix my signature.

MICHAEL BOTTINO.
